APPARATUS FOR DIVERTING MINERAL WOOL FROM BLOW ROOMS

Harold R. Harner, Ralph L. Lindemuth, and
Alton L. Jones, Joplin, Mo., assignors to The
Eagle-Picher Company, Cincinnati, Ohio, a
corporation of Ohio

Application January 24, 1945, Serial No. 574,412

2 Claims. (Cl. 154—27)

1

In the art of making mineral wool a stream of molten slag or rock is customarily atomized by a jet of steam. The threads so formed are blown by the force of the jet into a large chamber which is called the blow room. Heretofore it has been customary to remove all of the wool from the blow room by a single route, usually a conveyor. This system works very well when all of the wool is intended to be for the fabrication of a single product which is produced in volume sufficient to utilize the entire output. When, however, a number of products are to be made simultaneously and have slightly different requirements in the kind of mineral wool necessary for best results, the conventional system has grave faults. The class of wool must be separated outside of the apparatus in which the wool is primarily made. This entails great expense and often considerable hand labor. It is the object of the present apparatus to perform this separation immediately adjacent the blow room with an apparatus attached thereto. The apparatus of our invention merely performs two functions, i. e., separating the output of the blow chamber and simultaneously relieving the internal pressure on that chamber so that the flow of wool from the atomizing jet into the chamber is expedited.

Many mineral wool products furthermore cannot be made at high enough rate to utilize the full output of any large size cupola, say one producing two tons of molten charge per hour. Some operations can use only 500 pounds per hour. To slow down a large cupola to any such low production, or to maintain and operate a small cupola, increases cost and operating difficulties. By means of our invention, we maintain high volume production into a single large blow room, and divert therefrom the wool needed for low volume operations.

Normally only one such diversion system will be drawn from a blow room, leaving the bulk of the production move out of the blow room on the conventional bottom conveyor. In some instances, however, several such diversion lines may be drawn from a single blow room, thus enabling the simultaneous production of several mineral wool products.

The present invention is intended, for example, for an operation that requires a wool that is free from the so-called "shot" which is composed of small irregular but often spherical granules of molten slag or rock. The manufacture of insulating blankets demands, for example, a wool that is free from shot. Such a grade is desired for many other manufacturing purposes.

2

Referring to the accompanying drawings, Figure 1 is a side elevation showing a diversion unit in detail.

Figure 2 is a plan view of a blow room showing diagrammatically, three diversion installations each on a different side of the room.

10 is a conventional cupola from which a stream 11 of molten slag flows near the bottom into a jet of steam 12. 13 is the chamber usually called 10 a blow room which receives the filamentized products of the interaction of the steam jet and the molten slag or rock. This product is usually delivered at an upward angle of about 45°, 14 indicating the stream of wool projected into the blow room. The stream 14 drops onto the surface of 15 a belt conveyor 15 which runs on pulleys 16 along the bottom of the blow room and projects forwardly therefrom so as to be able to deliver the wool from the belt by gravity at 17 to the surface 20 of a cross conveyor 18 which carries the wool to a basic manufacturing operation, for example the preparation of insulating batts.

The apparatus as so far described is entirely conventional. The remainder of this description relates to our invention.

Near or on the top of the blow room either at the front side or rear thereof there is a vent pipe 19 of large diameter to which is connected a fan 20 which is preferably of the centrifugal separating type (i. e. fly-ash fan). This fan delivers by a spout 21 into a cyclone separator 22 from which the shot can be separated from the hopper bottom 23.

From the top of cyclone separator 22 an outlet pipe 24 extends in a preferably arcuate path which ends at the apex of a conical hood 25. The hood is located at a point which is just above the beginning of a conveyor at 26 leading to a place convenient to any further manufacturing operations that may have to be performed upon the product after it is in satisfactory form. The conveyor 26 is made preferably of wire screen and is at least as wide as any blanket that is desired to be made from the wool deposited upon it. Within the conical hood 25 there is a vertical adjustable conical deflector 27 mounted upon a vertical rod 28 which may be located in a number of vertical positions at different heights by means of a rack and pinion 29, the location of which is of no great importance. Under the foraminous belt 26 there is a suction area 30 which is at least as large as the sheet or blanket which it is desired to make in this apparatus. Its function is to assist and to speed up the deposits of particles of wool uniformly upon the belt 26 and to assist fan 20 to move the stream.

of wool particles flowing in air from the top of the blow room. 31 is the "cup" for applying the vacuum to the under side of belt 26 to a point between the pulleys 32. 33 is the outlet for a suction hose from the cup 31 to an exhaust fan.

The operation of the device is as follows: A proportion of the mineral wool floating in the air of the blow room is caught in the suction of fan 20 and enters a jet pipe 18 under this influence. The amount or proportion of wool which is so pulled out of the blow room depends upon the speed and capacity of a fan 20, the diameter of jet pipe 18, and the angle of the stream 14. All of these variations may be adjusted without departing from the spirit of the invention, and dampers, rheostats and other speed and volume control devices may be provided in appropriate places as is well known to those skilled in the art. The fan 20 and cyclone separator operate in the usual manner for the purpose of separating out the shot by centrifugal force. The shot is well adapted to being so handled, since it is granular and of considerably higher apparent density than the wool itself.

The hood 25 fulfills the function of spreading out the stream of wool delivered by pipe 24 to an area at least as large as the sheet of wool or blanket to be formed. An upward or downward adjustment of the conical deflector 27 may be necessary to consummate a uniform deposition of wool, but this adjustment can readily be performed by skilled operators. This deposition is assisted by the suction from the cup 31 which extends over the complete area defined by the demands of the blanket to be produced. The suction also holds the blanket close to the wire screen of the belt 26 so that the latter can easily move the formed blanket in a continuous strip from under the hood 25 so that the strip may be subdivided outside of the hood into pieces of blankets of any desired length. The absence of shot in blankets is very much to be desired, since their presence detracts from the insulating value of the wool and adds to its weight, and often it is desired to get as much insulating value in a given thickness and weight of blanket as possible.

It is to be understood that the conveyor 15 and 16, as well as the jet 12, fan 20, and cyclone 22, are to be continuously operated thus insuring a continuous output of a mineral wool sheet, the thickness of which is governed by the rate of deposition of the wool and the speed of conveyor belt 26, all of which may be adjusted.

We claim as our invention:

1. In combination with a mineral wool blow room, an apparatus connected to an elevated point in one of the walls of said room, said apparatus comprising suction means for exhausting

a portion of the wool contents of the blow room into the apparatus, pneumatic centrifugal means for purifying the wool of shot, pipe means for delivering the so purified wool to a conveyor, distributing means at the delivery end of said pipe for distributing the wool uniformly on the said conveyor, a foraminous conveyor positioned below said distributing means adapted to receive wool deposited thereon by the distributing means and 10 to form a continuous strip of wool and suction means arranged on the under side of said conveyor to suck continuously the air from the stream of wool being deposited on the upper conveyor surface through the conveyor belt whereby 15 to speed strip formation.

2. In combination with a mineral wool blow room, an apparatus connected to a point in the upper part of a wall of said room, said apparatus comprising an exhaust fan, a cyclone separator 20 connected to the delivery end of said fan to separate shot from wool passing through it, a pipe arranged to deliver de-shotted wool from said separator, a hood attached to the exit end of said delivery pipe, a generally conical regulator within 25 said hood, a rack and pinion adjustment for said regulator supported by said pipe whereby the height of the regulator may be adjusted within the hood to control the distribution of wool delivered to the hood, a foraminous conveyor arranged below said hood, a suction chamber 30 arranged below that part of the top surface of said conveyor which is covered by said hood, and an exhaust fan for creating reduced atmospheric pressure in said suction chamber.
